UNITED STATES PATENT OFFICE.

WILLIAM FEICKS, OF BLOOMFIELD, NEW JERSEY.

COKING AND GAS-GENERATING OVEN.

1,171,418.

Specification of Letters Patent. Patented Feb. 15, 1916.

Application filed January 22, 1912. Serial No. 672,771.

To all whom it may concern:

Be it known that I, WILLIAM FEICKS, a subject of the German Emperor, residing at Bloomfield, in the county of Essex and State of New Jersey, have invented certain new and useful Improvements in Coking and Gas-Generating Ovens, of which the following is a specification.

This invention relates to coking and gas generating ovens and has for its main object to improve the heating and methods for controlling the heating of such ovens.

Ovens of the above type have been known provided with vertical heating flues, and in which flues supplied with air and gas at their lower ends alternate with flues provided with air and gas supply at their upper ends. Such arrangement while preferable to firing all flues of an oven wall either from below or above is disadvantageous in that the oven construction turns out too complicated and expensive; and for this and other reasons has not been generally adopted. Furthermore, coking ovens are known in which sliding bricks or equivalent means are bodily inserted into the heating space of the oven walls, supported by the highly heated brick-work of the flues and having for their object to permit a separate regulation of the heating flues. Such regulating means are accessible by means of a rod inserted through closable openings in the oven structure above the heating flues. The drawback of such arrangement is that the regulating bodies are likely to bake with the flue brick-work due to the enormous heat prevailing and thus render the regulating bodies inoperable. The regulating bodies are also not easily interchangeable in case of their becoming defective.

The main object of the present invention now is to obviate all such defects in quite a novel and simple manner and thereby provide a more efficient coking oven.

The accompanying drawing illustrates two embodiments of the invention, the full scope and broadness of which is pointed out in the claims.

In the accompanying drawing: Figure 1 is a longitudinal section through a portion of an oven wall embodying my invention;

Fig. 2 is a longitudinal section through part of an oven wall according to this invention but of different construction than that shown in Fig. 1; Fig. 3 is a cross section on the line A—B in Fig. 1; Figs. 4 and 5 illustrate in

section and plan view respectively regulating bodies as here proposed, and Figs. 6 and 7 show in section and plan view an adjusting ring as employed in connection with said regulating bodies.

Referring to Figs. 1 and 3, 1 denotes the oven or retort chambers, 2 primary heating flues heated by partial combustion gases traveling in an upward direction, while 3 indicates secondary heating flues heated by products of complete combustion traveling in a downward direction. Flues 2 are provided at their lower ends with a gas supply through passages 4 and openings 5, and air supply by means of the passages 6 and ducts 7. The gas and air supplied to the lower ends of flues 2 may be such as to be regulatable in any desired manner and the air before admittance may, furthermore, be heated to any desired degree. The relative quantities of gas and air supplied to flues 2 is such, as to effect only partial combustion of the supplied gas in these flues or, in other words the quantity of air supplied with the gas is less than is required for perfect combustion. The products of combustion containing a larger or smaller quantity of unburnt gases as desired, pass upward in flues 2 through the upper connecting passages 8 to enter the flues 3. At this point additional air is supplied to the hot products to complete combustion of the unburnt gases. The products of combustion pass down the flues 3 through the lower ducts 9 into the passages 10 whence they may be disposed of as desired. The air supply to the upper ends of flues 3 is effected through passages 11 provided in the regulating bodies 12. These regulating bodies 12 and nozzles 13 for regulating the air passages are removably inserted through the openings 14, provided with covers 15. They extend into proximity to the passages between the primary and secondary heating flues and alter the cross sectional areas of said passages according to their adjustment therein. The general shape of the regulating bodies 12 with nozzles 13 is shown in Figs. 4 and 5.

The air before admittance to the passages 11 is subjected to a preheating in a system of channels 16 in the top part of the oven which may be connected with the atmosphere in any desired manner. The regulating bodies 12 are capable of a vertical adjustment so that their lower tapered ends may extend more or less within the restricted openings

17 of the heating flues 3. By raising or lowering these bodies the effectual cross section of flues 3 allowing passage for the products of combustion can be changed at will and thereby the heating of each group of heating flues can be separately and individually regulated. The vertical adjustment of these regulating bodies is obtained by rings 18 shown detailed in Figs. 6 and 7, which, as 10 the regulating bodies 12 and nozzles 13, are preferably made of fire clay or the like. These rings are placed under the collar 19 of the regulating bodies supporting the latter when in position. Any desired number 15 of such rings may be placed under the collar 19 thereby permitting adjustment of the bodies 12 within a great range.

In the construction shown in Fig. 2 always two adjacent flues are connected to 20 form a group, as against three in Fig. 1. This arrangement allows a more uniform heating of the oven walls than the construction shown in Fig. 1. The method of operation and general arrangement of parts here 25 shown is substantially the same as previously described, so that the same description may be read on all parts of Fig. 3 bearing the same reference numerals as before. The shape of the regulating bodies 12 in 30 this case differs slightly from the shape shown in Figs. 1, 3 and 5. In the construction shown in Fig. 2 the regulating bodies are designed to allow a regulation of the upper connecting passage 8, the effect obtained being the same as before.

For convenience of description and designation of the structural features in the 40 claims I have adopted in the claims for such heating flues forming uptakes for the heating gases the term primary heating flues, and for such heating flues forming down-takes for the heating gases the term secondary heating flues.

What I claim and desire to secure by Letters Patent is:—

1. In a coking or gas generating oven, upright heating flues in the walls thereof consisting of primary and interposed secondary heating flues, means for supplying 50 gas and air to the lower portions of said primary heating flues in such proportions as to effect only partial combustion of the gas in these flues, connections between said primary and secondary heating flues, regulating bodies, removably inserted into the oven structure through openings above the heating space formed by the oven wall and having their lower ends normally extended within restricted openings formed by the 55 heating flues, and air passages formed by said regulating bodies.

2. In a coking or gas generating oven, upright heating flues in the walls thereof, a series of regulating bodies inserted into 60 the oven structure through openings above

the heating flues, said regulating bodies being supported outside the heating space of the oven wall and having their lower ends normally extended into the upper connecting passages of the heating flues, means affording a vertical adjustment of said regulating bodies, air passages formed by said regulating bodies for conducting air into the heating space of the oven wall, and means for adjusting the air supply to such passages, such means as well as regulating bodies being accessible and removable through identical closable openings in the oven structure. 70 75

3. In a coke oven or gas furnace having primary and secondary heating flues in communication by passages, the combination of means for regulating the cross sectional areas of said passages, said means comprising devices arranged to be inserted in the oven walls in proximity to said passages and having passages for the supply of air. 80 85

4. In a coke oven or gas furnace having primary and secondary heating flues in communication by passages and means for supplying air and gas to said flues, the combination of nozzles supported in the oven walls and arranged in proximity to the passages, said nozzles having means for supplying additional air to said communicating 95 passages, and being adjustable in said oven, whereby the cross sectional areas of said passages may be regulated. 90 95

5. In a coke oven or gas furnace having heating flues in the walls thereof, some of said heating flues having restrictions at their upper ends, removable regulating plugs suspended through openings in the oven wall above said restrictions and having their lower ends normally extended within 100 said restrictions, the relative shape of the flue restrictions and the lower plug ends being such that the openings in the flues are increased or decreased according to the vertical position of the plugs, and means for 105 affording vertical adjustment of said plugs. 110

6. In a coke oven or gas furnace having upright heating flues in the walls thereof and upper connecting passages, removable regulating plugs suspended from the super-structure of the heating flues and having their lower ends normally extended through openings above some or all of the heating flues into the path of the heating gases for controlling the flow of the latter, said regulating plugs being provided with substantially vertical openings permitting inspection of the heating flues, and closable openings in the oven structure above the regulating plugs. 115 120 125

7. In a coke oven or gas furnace having primary and secondary heating flues in the walls thereof in communication by passages, some of such heating flues forming restrictions at their upper ends, removable regulat- 130

ing plugs suspended through openings in the superstructure above said restricted openings of the heating flues and having their lower ends normally extended within said 5 restricted openings, means affording a vertical adjustment of said regulating bodies and substantially vertical openings in said regulating bodies permitting inspection of the heating flues, and closable openings in

the oven structure above said regulating bodies.

Signed by me at Bloomfield, New Jersey this 20th day of January 1912.

WILLIAM FEICKS.
